SOLVENT REFINING PROCESS

Edward P. King, Beaumont, Tex., assignor to The Pure Oil Company, Chicago, Ill., a corporation of Ohio

Application May 23, 1951, Serial No. 227,873

13 Claims. (Cl. 196—14.42)

1
This invention relates to a method for increasing the efficiency of solvent extraction processes utilized in the refining of lubricating oils.

In the manufacture of lubricating oils from petroleum oil base stocks, it is frequently necessary to supplement the conventional treatments of lubricating oil stocks, such as distillation and/or clay treating processes, with various types of physical or chemical processes. The prime objective sought by the use of these supplemental processes is to free the lubricating oil stocks from all materials which have an adverse effect on the performance characteristics of the lubricating oils. In general, these undesirable materials which are contained in the base stock impart undesirable characteristics to the finished oil, namely, low viscosity index, high carbon residue and general instability.

The processes employed to effectuate the removal of these undesirable materials are generally classified as acid treating and solvent refining. In the former process the base stock is contacted with an acid such as sulfuric acid. The acid reacts with the various impurities to remove, in the form of an acid sludge, the undesirable constituents of the crude oil distillates being treated. Although this type of process has been used with considerable success in the preparation of lubricating oils, it has been found that lubricating oils refined by the solvent refining methods are generally superior to the sulfuric acid treated oils. As a result modern refining practices demand that solvent refining processes be employed in the general refining scheme utilized to produce a wide variety of saleable products from the crude petroleum oil processed by the refinery.

Solvent refining methods, which are physical in nature, are essentially simple in their basic principles in that the essence of these processes lies in the liquid-liquid contacting of a lubricating oil base stock with a solvent material having preferential solubility characteristics. As a result, the chemical composition of the hydrocarbon mixture treated is undisturbed. The initial contacting of the oil and solvent is carried out in an extraction tower in which countercurrent or concurrent contacting is employed. Due to the immiscibilities of the solvent and the lubricating oil base stock being treated, there occurs in the extraction tower a phase separation which permits the oil-rich phase or raffinate to be withdrawn from the treating tower as overhead and the solvent-rich phase or extract to be removed from the bottom of the tower. As in all contact mechanisms encountered in solid-liquid, liquid-

2
gas, or the liquid-liquid system employed in solvent extraction processes, there is frequently encountered due to the interfacial tension that exists at these various boundaries increased emulsification tendencies which result in an unfavorable effect on the ease of separation of the two phases into two separate and distinct layers. If a clean phase separation does not occur there will be either a carryover of the solvent-rich phase in the raffinate or, conversely, the oil-rich phase in the extract. These difficulties are generally present in all solvent extraction processes. It has been found, however, that these difficulties may be alleviated by carrying out the contacting of the oil and the solvent in the presence of small, added amounts of an ammoniacal reagent.

Accordingly, it is the object of this invention to provide a method of solvent refining which obviates or mitigates the phase separation difficulties encountered in solvent extraction processes.

A process flow diagram is shown in Figure 1 which schematically represents a conventional phenol extraction process.

It has been found that by carrying out the phenol solvent extraction of the undesirable constituents of a petroleum oil base stock in the presence of small, added proportions of ammonia that not only is the phase separation effectively enhanced but also the yield of the desired high viscosity index raffinate oil product is beneficially effected. Although ammonia has been employed as a refining agent in the phenol solvent extraction process, it has not been used in the manner taught by this invention and the beneficial results shown by this invention have not previously been made manifest. Hendrey in United States Patent 2,128,029 has utilized substantial amounts of anhydrous ammonia as a means for recovering the selective solvents of the phenol type. The recovery is accomplished by reacting the phenolic type solvent with the ammonia to form a compound which will readily break down under the proper conditions to liberate the recovered phenolic type solvent and ammonia for reuse in the process. The ability of ammonia to function as a solvent modifying agent when in combination with a phenolic type compound is shown by Arveson in United States Patent 2,092,199. In this latter process substantial amounts of ammonia are added to the phenol solvent. However, it will be noted that this combination solvent produces phase separation difficulties as it is brought out by the patentee that small quantities of water can be used to assist in overcoming this difficulty.

In contradistinction to the foregoing teachings, it has been found that when the petroleum oil base stock is contacted with the phenol solvent in the presence of small, added amounts of ammonia, certain beneficial results are shown which are not evident from and are contrary to the teachings of the prior art.

The chemistry of surface active agents has had considerable application in many fields related to the petroleum industry. A notable example being the use of surface active agents in the demulsification of oil and water emulsions encountered in the production of crude petroleum oils. While the use of surface active compounds has been widely investigated in aqueous media, very little attention has been directed to their use in non-aqueous media for the surface active agents are not generally prepared for this purpose. It has been found, however, that apparently surface active chemistry has its application in increasing the efficiency of solvent refining processes wherein a non-aqueous media is employed as a solvent. To facilitate a better understanding of the invention a brief description of a typical phenol extraction process will not be amiss. Referring now to Figure 1, it will be seen that in general the several process streams encountered in a phenol extraction process are four in number and will be discussed separately. Initially, the preheated petroleum oil charge stock, which may consist of a low, intermediate or high viscosity lubricating oil stock obtained as a side stream from the vacuum distillation of a topped crude or the deasphalted residuum produced in the vacuum distillation process, is introduced by means of line 10 into a phenol absorber tower 11 wherein it is countercurrently contacted with a constant boiling mixture of phenol and water obtained from a hereinafter mentioned source. This initial treatment effects the removal of the phenol from this constant boiling mixture thereby eliminating the necessity for employing a distillation process for separating the constituents of this phenol-water mixture, the separation of which would be extremely difficult because of the closeness of the boiling points of the distillate and the mixture from which the distillate is being produced. The process water is removed in the vaporous state from the absorber tower 11 by line 12 which transfers the phenol-free water to the waste disposal system of the refinery. The charge stock containing minor amounts of phenol removed from the phenolic water is then passed by line 13 to the extraction tower 14 where it is countercurrently contacted with the phenol solvent to extract the undesirable constituents from the lubricating oil base stock. The phenol employed in this operation is introduced into the top of the extraction tower 14 by means of line 15 which connects the extraction tower 14 with the phenol storage facility 16. Because of their immiscibility, the two liquids contacted in the extraction tower 14 separate into two phases, namely, an oil-rich or raffinate phase which is withdrawn from the top of the extraction tower 14 by means of line 17, and a solvent-rich or extract phase which is withdrawn from the bottom of the treating tower 14 by means of line 18. Considering first the raffinate, this overhead product is transferred from the extraction tower 14 by means of line 17 to the evaporator section of the raffinate tower 19. While being transferred, it passes through the raffinate furnace 20 wherein it is

heated to an elevated temperature sufficient to effect in the evaporator section the flash distillation of the phenol constituent of the raffinate phase. The raffinate solution containing minor amounts of phenol is then introduced into the stripping section of the raffinate tower 19 by means of line 21. In this section the raffinate is denuded of trace amounts of the remaining phenol by means of steam stripping. The finished raffinate is then removed from the bottom of the stripping section by means of line 22. The thus treated raffinate, having distinctly improved characteristics of viscosity index, carbon residue, and general stability, may then be passed to subsequent processing steps such as solvent dewaxing, clay contacting or various blending operations to produce the finished lubricating oil. With regards to the extract which is withdrawn from the bottom of extraction tower 14 by means of line 18, it will be seen from Figure 1 that this product is introduced at an elevated temperature to an extract dryer 23 wherein all of the water which is contained in the extract phase is separated therefrom. There is also effected a partial phenol separation at this step and as a result the water and phenol are removed by line 24 as a vaporous, constant boiling mixture of phenol and water. The elevated temperature required for this dehydration may be obtained by passing the extract solution in indirect heat exchange with other process streams or other suitable means. The anhydrous extract still containing some quantities of phenol is then withdrawn from the bottom of dryer 23 and transferred via line 25 to the extract flash tower 26 wherein most of the remaining phenol is separated by flash distillation. This phenol is removed as overhead effluent by line 27 by means of which it is returned to the phenol storage 16. An extract furnace 28 is employed in conjunction with the extract flash tower 26. This furnace 28 in effect acts as a reboiler for the extract flash tower 23 to insure the substantial removal of most of the phenol from the anhydrous extract which is fed into the flash tower 26. The bottoms from the flash tower are then fed by line 29 into the extract stripper 30. In this vessel, the remaining traces of phenol contained in the anhydrous extract are eliminated by means of steam stripping. The extract oil is removed from the bottom of the stripper 30 by means of line 31. Although this extract oil contains the undesirable constituents separated from the lubricating oil base stock it is however a marketable product which may be blended in with fuel oils or used as a compounding agent in other types of composition.

The two remaining streams to be considered are the phenol streams and the phenolic water streams. As it has been pointed out above the phenol solvent initially used is introduced into the extraction tower 14 by means of line 15. The phenol solvent is then carried from the extraction tower 14 to the recovery section of the solvent refining process by the raffinate and extract streams. The separation and recovery of the phenol solvent from these respective streams is effected in the raffinate tower 19, the extract dryer 23, the extract flash tower 26, and the extract stripper 30. The anhydrous phenol which is recovered from the evaporator section of the raffinate tower 19 is returned to the phenol storage 16 by line 32. The phenol recovered from the extract flash tower 26 is returned to the phenol storage 16 by line 21. The remain-

ing amounts of phenol are recovered from the system in the form of mixtures of phenol and water. These phenolic water streams originate as overhead effluent streams from a number of locations, namely, the stripping section of raffinate tower 19, the extract dryer 23, and the extract stripper 30. The phenolic vapors (90% phenol and 10% water) recovered from the stripping section of raffinate tower 19 and the extract stripper 30 are condensed and transferred to a phenolic water accumulator 33, by means of lines 34 and 35, respectively. Phenolic water vapors from the dryer (90% water and 10% phenol) are condensed and collected in phenolic water accumulator 33". Reflux in the form of phenolic water is withdrawn from the phenolic water accumulator 33" and returned to the extract dryer 23 by line 36. Non-condensed or excess phenolic water vapors are transferred via line 24, or by means of the steam ejector 37 through line 38 to the phenol absorber tower 11 wherein the phenol constituent of the phenolic water mixture is separated by contact with the preheated charge stock introduced into the tower as hereinbefore mentioned. The mixture of phenol and water obtained from extract dryer 23 is transferred to the phenol recovery system by means of line 24 which interconnects with line 38, returning the phenolic water to the phenol absorber tower 11. It will be noted that not all of the phenolic water is returned to the phenol absorber tower 11. In addition to that which is employed as reflux in the extract dryer 23, quantities of the phenolic water may also be introduced into the bottom of the extraction tower 14 by means of line 39, or into the tower with the oil feed via line 39". This phenolic water is introduced near the bottom of the extraction tower 14 for two purposes, firstly, to increase internal refluxing, and secondly, to raise the immiscibility temperature of the phenol with the oil charge stock. The addition of this phenolic water changes the solvent characteristics of the phenol and the amount of phenolic water introduced into the extraction tower must be properly balanced to provide maximum efficiency.

In carrying out the instant invention, in one of its embodiments, it has been found that by adding ammonia to the phenol and phenolic water streams, it is possible to improve the operation of the phenol extraction process by improving the tower extraction efficiency. In accordance with this particular embodiment ammonia is delivered from the ammonia supply source 40 into the respective phenol and phenolic water lines by means of line 41 and the branch lines 42, 43, 44, 45 and 46. Although any suitable source of supply of ammonia may be employed, it has been found liquid ammonia will provide an appropriate means for introducing the desired amounts of ammonia into the system. Line 42 is employed to introduce ammonia into the phenolic water recovered from the stripping section of the raffinate tower 19. Line 43 is similarly employed to introduce ammonia into the phenolic water overhead from extract stripper 30. Line 44 introduces ammonia to the extract dryer whence it is recovered in the overhead which is condensed in phenolic water accumulator 33". Line 45 is employed to introduce ammonia into the anhydrous phenol recovered as the flash distillate from the extract flash tower 26. Line 46 serves the same purpose in introducing ammonia into the phenol overhead recovered from the flash section of raffinate tower 75

19. Although the ammonia may be introduced into the system at any point whereby the initial extraction is carried out in the presence of ammonia, it is preferred to introduce the ammonia at the above points in order that advantage may also be taken of the inherent acid neutralization properties of ammonia to minimize the corrosion occurring in these lines due to the acidic nature of the phenolic streams. The main objective, however, of the instant invention is to enhance materially the efficiency of the extraction step of the solvent extraction process. This is effectuated in one form by the addition of minor amounts of ammonia to the phenol and phenolic water streams. The effect of the invention is also illustrated by the tabular summary in Table I in which the results obtained when injecting ammonia at those points illustrated in Figure 1 are compared with conventional operations.

Table I

Run No.	1	2	3
25			
Ammonia injected	None	None	20-25 lbs./day. 0.02% by wt.
Ammonia concentration in treating tower	None	None	
Charge, B./D.	5.315	5.120	5.200
Raffinate yield, Vol. percent	66.1	67.8	67.0
Raffinate Gravity, °API	32.5	32.4	32.7
V. I.—Finished Oil	101	100.3	102.4
Extract Gravity, °API	11.1	10.3	11.0
Phenol/Oil—Vol. Ratio	1.71	1.99	1.74
Water to treating tower (Vol. percent of Solvent):			
To Bottom	7.1	8.6	7.8
To Top	0.6	None	None
35			
Treating tower temp.: Top—°F	135	131	124
Bottom—°F	117	130	123

It is noted from Table I that when ammonia is introduced into the system as illustrated by run No. 3, a slightly decreased yield of increased viscosity index was obtained with a lower phenol/oil ratio. This improvement in viscosity index is obtained in spite of a reduced treating ratio. This improvement is attributed to the enhancement in phase separation resulting from the use of ammonia injection. Run No. 1 is shown to compare the effect evidenced when water is added to the phenol entering the top of treating tower to assist in phase separation. This addition of water may be introduced into the treating tower by means of line 47 shown on the Figure 1 if it is so desired. It will be noted, however, that although phase separation and the carryover of the phenol-rich phase with the oil-rich raffinate phase is reduced by the addition of water to the top of the extraction tower 14, the yield and the viscosity index of the product obtained is lower than those shown in run No. 3 when ammonia was being injected. In both of these instances the phenol/oil ratio was substantially the same. Run No. 2 is included to show the effect on viscosity index and yield when neither water nor ammonia is employed to increase the efficiency of the tower extraction process. From the results of run 2, it is seen that in spite of the higher phenol/oil ratio the viscosity index of the finished raffinate is lower than that obtained in runs 1 and 3. Although a higher yield resulted in run 2, this advantage is offset by the lower viscosity index of product obtained in run 2. The improvements in the properties of the raffinate oil product, however, are incidental to the major improvement in the operation of the solvent extraction process resulting from the addition of ammonia to the system, namely, improved phase separation in the ex-

traction tower. From this improvement results less solvent carryover in the raffinate phase and reduced solubility of the oil in the phenol and provides a solution for a bothersome operation problem resulting from emulsion difficulties occurring in the extraction tower.

While it is seen that the introduction of ammonia into the phenol and water stream of a phenolic solvent extraction process materially improves the efficiency of phase separation in the extraction operation and provides increased yields and improved quality of products over conventional operations, the theory of operation is not clearly understood. It is thought that the improved operation results from an improvement in the interfacial tension relationships existing at the liquid-liquid boundaries that occur from tray to tray in the extraction tower. Most lubricating oil stocks contain organic acids. While the less volatile acids such as naphthenic acid are recovered in the extract, the more volatile ones such as acetic remain in the system in the circulating phenolic streams. These volatile acids may react with the ammonia to form ammonical organic salts which function as surface active agents. It is also possible that the ammonia alone or in some combination with phenol or water or both may function as a surface active agent in the media composed of oil, phenol and water and provide the desirable result shown by this invention. However, these explanations are merely postulations and it is not intended to limit the scope of the instant invention thereby.

The optimum quantity of ammonia that is employed must be determined experimentally. It is obvious that an amount less than that which would react with substantial amounts of the phenol solvent to form precipitant reaction products which would clog up the process lines and vessels should be employed. It has been found that in operating a unit having a capacity of about 5200 barrels per day, and processing a petroleum oil feed stock obtained from a Mid-Continent crude, if about 20 to 25 pounds per day of ammonia are introduced into the system, after building up a concentration of between 0.01 and 0.05% by weight of material in the treating tower, the emulsification problems encountered in the extraction tower of the process are minimized. Although the amounts consumed are equivalent to between about 0.0012-0.0016 percent by weight of lubricating oil feed stock charged to the unit, the concentration existing in the phases within the treating tower is maintained at more than ten times this amount by recirculation of the ammonia with the water and phenol in the recovery system. The distribution of ammonia between phases in the tower has not been precisely evaluated but it is known that the greater proportion of ammonia is held in the phenol extract phases. If greater concentrations are desired or needed the extraction tower may be operated under superatmospheric conditions to obviate gasification problems that might arise through the use of increased amounts of ammonia or other similar ammoniacal compounds.

Although from the above it is seen that the ammonia has been introduced into the system by means of the oil-free, phenol-containing streams, it is evident that the scope of the invention should not be so limited. Any expedient whereby ammonia is introduced into the extraction tower in amounts sufficient to enhance the phase separa-

tion resulting therein should be considered to be within the purview of the instant invention. It is to be further noted that although ammonia is the preferred reagent employed in accordance with this invention other ammoniacal compounds or compounds which will produce ammonia in the treating tower environment may be utilized. Ammonium salts are relatively unstable materials which dissociate upon being exposed to moderately elevated temperatures. Examples of such compounds which would dissociate under the ambient conditions encountered in the extraction tower include the acetate, perborate, carbamate, carbonate, citrate, fluoride, hydroxide, molybdate, nitrite and sulfide of ammonium. The use of these compounds may produce undesirable solids or corrosive products upon dissociation which would deleteriously affect the treating operation or the refined product unless removed therefrom at some stage. It is for this reason that the use of ammonia per se is the preferred embodiment of the instant invention.

It is therefore seen that tower extraction efficiency of a phenol extraction unit is materially improved by carrying out the contacting of the petroleum oil and phenol solvent in the presence of small, added amounts of ammonia. The ammonia may be introduced into the system by the addition of ammonia to the phenol and phenolic water streams which are employed in the recovery system of the solvent refining process or any other suitable means.

What is claimed is:

1. In a solvent refining process for improving the viscosity index of a mineral oil lubricant wherein a petroleum oil is contacted with a phenol solvent to produce an oil-rich phase and a solvent-rich phase, the improvement comprising maintaining within the contacting zone a material selected from the group consisting of ammonia and ammoniacal compounds which decompose to liberate ammonia under the conditions of operation of said process, said material being present in small amounts up to the equivalent of about 0.05 per cent by weight of ammonia based on the amount of phenol and oil in said contacting zone, but sufficient to enhance phase separation between the oil-rich and the solvent-rich phases.
2. A process in accordance with claim 1 in which the material is ammonia.
3. In a solvent refining process for improving the viscosity index of a mineral oil lubricant wherein a petroleum oil is contacted with a phenol solvent to produce an oil-rich phase and a solvent-rich phase, the improvement comprising maintaining within the contacting zone a material selected from the group consisting of ammonia and ammoniacal compounds which decompose under the conditions of operation of said process to liberate ammonia, said material being present in an amount sufficient to provide 0.01 to 0.05 per cent by weight of ammonia based on the amount of phenol and oil in said contacting zone.
4. In a solvent refining process for improving the viscosity index of a mineral oil lubricant wherein a petroleum oil is contacted with a phenol solvent to produce an oil-rich phase and a solvent-rich phase, the improvement comprising maintaining within the contacting zone of said solvent refining process a concentration of from .01 to .05 per cent by weight of ammonia based on the amount of phenol and oil in said contacting zone.

5. In a phenol extraction solvent refining process for improving the viscosity index of a mineral oil lubricant wherein a raffinate phase and an extract phase are produced in the extraction zone of said process, the improvement comprising introducing into the circulating phenol-containing effluents recovered from said raffinate and extract phases prior to recycling these effluents to said extraction zone from .0012 to .0016 per cent by weight of ammonia based on the amount of oil charged to said process.

6. In a solvent refining process for improving the viscosity index of a mineral lubricating oil wherein a petroleum oil is contacted with a phenol solvent to produce an oil-rich phase and a solvent-rich phase, the improvement comprising introducing into the contacting zone of said process a material selected from the group consisting of ammonia and ammoniacal compounds which decompose to liberate ammonia under the conditions of operation of said process, said material being added in an amount sufficient to supply .0012 to .0016 per cent by weight of ammonia based on the amount of oil charged to said process.

7. In a solvent refining process for improving the viscosity index of a mineral oil lubricant wherein a petroleum oil is contacted with a phenol solvent to produce an oil-rich phase and a solvent-rich phase, the improvement comprising introducing into the contacting zone of said process from .0012 to .0016 per cent by weight of ammonia based on the amount of oil charged to said process.

8. In a solvent refining process for improving the viscosity index of a mineral oil lubricant wherein a petroleum oil is contacted with a phenol solvent to produce an oil-rich phase and a solvent-rich phase, the improvement comprising introducing into the contacting zone of said process ammonia in amounts sufficient to build up within said contacting zone a concentration of .01 to .05 per cent by weight of ammonia based on the amount of phenol and oil in said contacting zone and thereafter introducing into said contacting zone from .0012 to .0016 per cent by weight of ammonia based on the amount of oil charged to said process.

9. A method in accordance with claim 8 in which the said petroleum oil feed stock contains volatile organic acids.

10. A method in accordance with claim 8 in which the said petroleum feed stock is prepared from a Mid-Continent crude.

11. In a solvent refining process for improving the viscosity index of a mineral oil lubricant wherein a petroleum oil is contacted with a phenol solvent to produce a raffinate phase and an extract phase, the improvement comprising building up within the contacting zone of said process a concentration of from .01 to .05 per cent by weight of ammonia based on the amount of

phenol and oil in said contacting zone and thereafter introducing into the circulating phenol-containing effluents recovered from said raffinate and extract phases prior to recycling said effluents to said contacting zone from .0012 to .0016 per cent by weight of ammonia based on the amount of oil charged to said process.

12. In a solvent refining process in which a petroleum oil feed stock is contacted in an extraction zone with a phenol solvent to produce an oil-rich raffinate phase and a phenol-rich extract phase, the improvement comprising subjecting the said raffinate phase to a flash distillation wherein phenol vapors are recovered as overhead products, steam stripping a flash distillation residue to produce an overhead product consisting essentially of phenol and water and a bottoms product consisting of the desired high viscosity index raffinate oil, passing said extract phase to a drying zone and recovering therefrom as overhead product a constant boiling mixture of phenol and water, flash distilling the dried extract solution, recovering as overhead therefrom a substantial portion of the remaining phenol solvent, steam stripping the remaining extract to remove the residual traces of phenol solvent, thereby producing an overhead product consisting of phenol and water and a bottoms product consisting essentially of phenol-stripped extract containing low viscosity index constituents, introducing into the aforementioned phenol-containing overhead products from .0012 to .0016 per cent by weight of ammonia based on the amount of oil charged to said process and recycling said ammonia-containing phenol to said extraction zone to contact additional amounts of said petroleum oil feed stock.

13. In a phenol extraction solvent refining process for improving the viscosity index of a mineral oil lubricant wherein a raffinate phase and an extract phase are produced in the extraction zone of said process, the improvement comprising introducing into the circulating phenol-containing effluents recovered from said raffinate and extract phases prior to recycling said effluents to said extraction zone a material selected from the group consisting of ammonia and ammoniacal compounds which decompose under the conditions of operation of said process to liberate ammonia, said material being added in an amount sufficient to provide from .0012 to .0016 per cent by weight of ammonia based on the amount of oil charged to said process.
